HORATIO N. BILL, OF WILLIMANTIC, CONNECTICUT.

Letters Patent No. 97,861, dated December 14, 1869.

STOVE-PIPE THIMBLE.

The Schedule referred to in these Letters Patent and making part of the same.

To all whom it may concern:

Be it known that I, HORATIO N. BILL, of Willimantic, in the county of Windham, and State of Connecticut, have invented a new and improved Adjustable Stove-Pipe Thimble; and I do hereby declare that the following is a full, clear, and exact description thereof, which will enable others skilled in the art to make and use the same, reference being had to the accompanying drawings, forming part of this specification.

This invention relates to improvements in thimbles for the passage of stove-pipes through the walls into flues; and consists in providing a vertically-sliding thimble-plate in a metallic frame, having a long opening, and adapted for insertion in an opening through the wall, so as to support the thin plate at or about the line of the inner face of the flue-wall, so that the plate may be drawn up or down, to vary the height of the thimble for pipes of different vertical lengths.

The invention also comprises an improved mode of attaching the thimbles to this plate by means of radial studs at the rim, separated from the main part of the rim, and bent inward, so as to pass through slots in the thimble-plate around the hole, to engage behind the edge of the plate by turning the thimbles on their axes a short distance, after being passed through the slots, while the main part of the rims of the said thimbles bear against the front face of the thimble-plate and cover the slots when so turned.

Figure 1 represents a front elevation of my improved device;

Figure 2 represents a rear elevation of the same;

Figure 3 represents a sectional elevation of the same; and

Figure 4 represents a plan view of a thimble.

Similar letters of reference indicate corresponding parts.

A is the thimble-plate, consisting of a long strip of metal, of any suitable kind, preferably sheet-metal, and provided with a circular hole, B, for the thimble.

This plate is notched around the hole, as shown at C, and the plate is fitted to slide up and down in a long metal or other frame, D, and adapted for insertion in an opening through the wall, and provided with guides E at the rear.

F is a button or pawl attached to the rear side of the plate, to bear against the guides E, or against the wall of the opening through the brick wall, to hold the plate at the required height.

The thimbles G, are stamped in any required form, and cut from the periphery inward a suitable distance to form projections, H, which, being suitably set or bent inward at the bottom of the cuts, will pass through the notches C in the plate, and, being turned on the axis of the thimble, will engage behind the plate A, to hold the thimbles in place, while the other parts of the rim will cover the notches C.

These thimbles are to be made with holes of different sizes, for pipe of different size, and are to be interchanged as required, while the height of the hole is varied by sliding the plate up or down.

It is intended to arrange these frames so that the plates A may be reached through the fire-place, by any suitable device, for changing them, or they may be pressed up or down by the application of force at the outside, in any suitable way.

In the latter case, the button will be arranged so as to be raised out of contact with the wall from the outside for lowering the plate.

The projections of the thimbles and the parts of the plates behind which they turn, are arranged to have sufficient draw in a spiral direction, to clamp the two tightly together.

Having thus described my invention,

I claim as new, and desire to secure by Letters Patent—

1. The combination, with a frame, D, provided with grooves or guides E, and adapted for application in openings in the flue-walls, as described, of the sliding thimble-plate A, provided with an opening, B, for the reception of a pipe or thimble, substantially as specified.

2. The mode of attaching the thimbles G to the plates A, by means of the bent projections H on the former, passing through the notches C in the plates, and turning behind the parts of the plate adjacent to the notches, substantially as specified.

3. The combination of the plate A, frame D, and button F, all constructed and arranged substantially as specified.

The above specification of my invention signed by me, this 16th day of October, 1869.

HORATIO N. BILL.
